UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

COMBINED RAIL-BRACE AND TIE-PLATE.

Specification of Letters Patent. Patented Dec. 20, 1910.

979,350.

Application filed December 7, 1909. Serial No. 531,782.

To all whom it may concern:

Be it known that I, JOHN W. STEPHENSON, of Toledo, Lucas county, Ohio, have invented a new and useful Combined Rail-Brace and Tie-Plate, of which the following is a full, clear, and exact description, reference being had to the accompanying drawings, forming part of this specification, in which—

Figure 1 is a plan view of a combined rail brace and tie plate embodying my invention and shown applied to a track rail; Fig. 2 is a section on the line II—II of Fig. 1; Fig. 3 is a section on the line III—III of Fig. 2; Fig. 4 is a vertical section through the brace member; Fig. 5 is a plan view partly in horizontal section showing a modification; Fig. 6 is a section on the line VI—VI of Fig. 5; and Fig. 7 is a vertical section through one of the brace members of Fig. 5.

My invention has relation to combined tie plates and rail braces for railway tracks; and is designed to provide a device of this character which is simple in its construction; which will hold the rail securely in a manner to prevent creeping thereof; which will provide a strong brace for the rail, and also an efficient support for the head thereof; and which is provided with means for preventing the brace members from becoming loose in service.

Referring first to the construction shown in Figs. 1 to 4, inclusive, the numeral 2 designates a tie plate member provided with the usual spike holes 3 for securing it to the tie, and having near one edge an undercut lip or flange 4 adapted to engage one edge of the base flange 5 of the track rail 6. At the opposite side of the rail the member 2 is formed with the transversely extending upward projection 7 having the bracing ribs or webs 8. The projection 7 is inclined as shown, to give a beveled undercut inner face, and is also inclined to the vertical plane of the web of the rail.

9 designates a brace member, which is adapted to fit between the inner beveled or undercut face of the projection 7 and the rail. This member is shown as having a portion 10 which fits against the base of the rail, an upper portion 11 which fits underneath and forms a support for the top flange of the rail, and a portion 12 which seats between the outer edge of the rail and the inner face of the projection 7. The outer face of this portion 12 is inclined in

two directions to fit the double inclination of the inner face of the projection 7.

13 is a bolt, which extends through the brace member and through the web or flange 8 at the opposite edge of the tie plate 60 member, and which is secured by a nut 14. Any suitable or usual nut locking device may be provided to prevent this nut from working loose.

The web or flange 8 is shown as being 65 extended to the inner side of the projection 7 to receive the bolt 13, and also to form a tie between the inner side of said projection and the base portion of the plate. This tie function of the flange 8 is of great practical 70 importance, since it prevents spreading of the projection 7 when the brace member is driven to its seat.

In applying the device to the rail, the brace member 9 is inserted between the rail 75 and the projection 7, and is tightly driven to its seat, the transverse inclination of the inner face of the projection 7 causing it to become firmly wedged in position. The parts are preferably made of malleable 80 castings, and the brace member can be very firmly wedged in place by driving. The bolt 13 is then inserted and secured.

Should any looseness develop in service by reason of wear, the brace member can be 85 driven to take a new bearing at any time.

In the modification shown in Figs. 5 to 7, the upward projection 7^a corresponding to the projection 7 of the form first described, is provided with a double transverse bevel 90 on its inclined inner surface, as shown at 15 and 16 in Fig. 5. Two brace members 17 and 18 are employed, these brace members being inserted from opposite sides of the tie plate and driven toward each other upon 95 the oppositely beveled faces 16 and 17. A bolt 19 is then inserted through openings in both brace members, and is secured by a nut 20 which may also be provided, if desired, with any suitable nut-locking 100 means. In this form of the invention, the two brace members hold against each other, since any tendency of one to work loose is resisted by the other member.

It will be noted that the form of the brace members in both forms of my invention is such as to cause them to form a very rigid brace for the rails; in fact, when these members are properly driven and secured, the entire device is practically a one-piece 105 110

structure. The braces also extend underneath practically the full width of the overhanging flange of the head of the rail so as to form a full support for the same.

5 When the securing bolts are properly fastened, it makes it impossible for the brace members to work loose in service.

It will be obvious that various changes may be made in the construction and arrangement of the parts, without departing 10 from the spirit and scope of the invention as defined in the appended claims. Thus, while I have shown the brace members as of cored or hollow form to reduce their 15 weight, it is obvious that solid braces may be employed if preferred, and that various other changes may be made in the form of the parts.

What I claim is:—

- 20 1. In a combined rail brace and tie plate, a tie plate member having a transversely extending upward projection at one side of the rail, said projection having an inner face which is inclined downwardly and outwardly and also transversely, and a brace member seated between the said projection and the rail and extending upwardly underneath the head of the rail, together with a securing bolt passing 25 through the brace member and having a bearing at one end in said projection, the bolt-bearing portion of said projection also forming a tie between the inner side of

the projection at one end and the base portion of the tie plate to prevent spreading 35 of said projection when the brace member is driven to its seat; substantially as described.

2. In a combined rail brace and tie plate, a tie plate member in the form of a casting 40 having a base portion to extend underneath the rail and formed at one side of the rail with an upwardly extending inclined projection, and a plurality of webs or ribs extending from the rear side of said projection toward the adjacent end of the plate and reinforcing and bracing the projection, one of said webs or ribs being extended beyond the end of the projection to form a tie 45 between the inner side thereof and the base 50 of the plate; substantially as described.

3. In a rail brace, a seating member having an upward projection formed with an inner face inclined downwardly and outwardly and also transversely, and a web 55 or flange connecting the inner side of said projection at one end with the base portion of said member, said flange also having an opening therein for a securing device; substantially as described.

In testimony whereof, I have hereunto 60 set my hand.

JOHN W. STEPHENSON.
